UNITED STATES PATENT OFFICE

2,563,761

SOCKET CONNECTOR HAVING AN
INDENTED SOLDER WALL

William A. Uline, Sidney, N. Y., assignor to Ben-
dix Aviation Corporation, South Bend, Ind., a
corporation of Delaware

Application September 20, 1945, Serial No. 617,561

1 Claim. (Cl. 173—363)

1

This invention relates to electrical connectors, and particularly to connectors of the pin and socket type.

The connectors of the present invention are adapted to uses similar to those described in my copending applications Serial Numbers 611,372 and 611,374 and my Patent No. 2,521,056, issued September 5, 1950, but are particularly adapted to manufacture in small sizes, for instance in sizes having a diameter of about 0.1 inch or less. In such sizes the making of socket type connectors of the kinds heretofore known is difficult, expensive, and not too satisfactory.

It is an object of this invention to make electrical connectors of the socket type that are adapted to satisfactory methods of manufacture, are useful in all sizes, but that are particularly adapted for manufacture in small sizes.

The objects of the invention are accomplished generally speaking by a connector all the essential parts of which are integrally formed from a tube by simple operations that can be performed with facility even upon tubes of small sizes.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claim.

In the drawings, wherein like reference characters refer to like parts throughout the several views,

Fig. 1 is a plan view of a socket type connector of a preferred type;

Fig. 2 is a full scale plan view of a small size connector of the type shown in Fig. 1;

Fig. 3 is a vertical section through a semi-finished connector of the type shown in Fig. 1 constructed according to the principles of the invention.

In a preferred embodiment of the invention, as shown in Fig. 1 and Fig. 3, a length of tubing 10 that is preferably made of beryllium copper is swaged inwardly at points 120 degrees apart at a sufficient distance from the end of the tube to form a solder well, and the end of the well is milled as at 11 to admit the end of a conductor such as copper wire, and solder. The swaging should be such that no light shows through the tube. In the figure of the drawing the swaged indentations are indicated by the numeral 12 and

5

are three in number, but there may be more or fewer of them, whenever an advantage is gained thereby. In this solder well the end of the connector is automatically centered by the indentations.

10 In the manufacture of the connector several longitudinal slots 15 are milled in the wall of the tube between the indentations 12 and the end 16 of the tube. This stage of manufacture is indicated in Fig. 3. Thereafter the strips 17 between the slots are bowed inwardly as shown in Fig. 1, and the socket is heat treated. The outer end 16 of the socket may thus be made larger than the pin it is to receive without affecting the firmness 15 of the electrical connection. After the heat treatment the socket may be silver plated, a plating of .0003 to .0004 inch thickness being satisfactory for most purposes.

15 The construction prior to the bowing of the strips is shown in Fig. 3. If burrs are formed by milling the slots they should be removed, but some interior surface roughness is not objectionable. Strip spring tension is set in a die prior to heat treatment. The tension should be set so that about $\frac{1}{4}$ pound to 2 pounds pull is required to withdraw a #16 or 20 pin from a socket. The pressure increases with the size of the pin and the contacts.

20 The pins employed may be of any satisfactory type, for instance such as are disclosed in my copending application Serial No. 611,374.

When so constructed the socket of Fig. 1 is capable of furnishing strong support and extensive contact areas to a pin connector, so that the resistance of the connection is favorably low, a condition difficult to obtain in sockets of such small size. The socket gives a long, easy acting spring that is practically incapable of being overstressed and destroyed.

25 40 A particular advantage of the invention is in that the spring fingers or strips are supported at both ends, which contributes firm contact with a minimum of mass and weight. Another advantage is a novel method of making novel connectors in small sizes.

45 50 Although only one embodiment of the present invention is herein illustrated and described, it is to be expressly understood that the same is not limited thereto. Various changes may be made therein, particularly in the design and arrangement of the parts illustrated without departing from the spirit and scope of the invention, as will now be apparent to those skilled in the art.

What is claimed is:
An electrical connector consisting of a metal

2

tube having a socket connector at one end and a solder well at the other separated by a closed wall, said connector tube having a plurality of circularly arranged indentations forming said wall between said ends.

WILLIAM A. ULINE.
